UNITED STATES PATENT OFFICE.

VICTOR MÜLLER, OF PHILADELPHIA, PENNSYLVANIA, ASSIGNOR OF ONE-HALF TO
JOHN SIMMONS COMPANY, OF NEW YORK, N. Y., A CORPORATION OF NEW YORK.

APPARATUS FOR CUTTING THREADS ON TUBES AND FOR CUTTING OFF TUBES.

Application filed November 8, 1921. Serial No. 513,710.

To all whom it may concern:

Be it known that I, VICTOR MÜLLER, a citizen of the German Republic, and a resident of the city of Philadelphia, in the 5 county of Philadelphia, in the State of Pennsylvania, have invented certain new and useful Improvements in Apparatus for Cutting Threads on Tubes and for Cutting Off Tubes, of which the following is a 10 specification.

The present invention relates to a combined threading and cutting off machine for tubular bodies, and has for its purpose to provide a machine of that character 15 wherein the piece to be worked may be threaded on both ends at the same time and cut without removing the piece from its originally secured position, thereby considerably reducing the cost of manufacture of 20 this material and considerably expediting the time in which the work may be done, and wherein the cost of installment may be considerably reduced, because the apparatus 25 can be easily attached on any present pipe threading machine, using hereby all the frame and driving and clamping parts of the same and scrapping only the old die-head, in whose place the object of the invention will be installed.

30 The apparatus forming the subject matter of this invention performs all these operations, that is, threading two ends of pipe at the same time and thereafter cutting off the finished piece, entirely automatically 35 and thereafter stops the functioning of the apparatus, thus informing the operator when the stock or material has to be shifted and reclamped in the machine. These automatic functions of my new apparatus enable 40 the operator to attend a number of machines at the same time because his only service will be in removing and clamping the material stock.

With these advantages, the present invention 45 embodies other points of merit, which will be set forth in the course of the following extended description and the appended claims.

Referring to the accompanying drawing 50 wherein is shown the invention in its preferred embodiment:

Fig. 1 is a longitudinal sectional view of the machine,

55 Fig. 2 is a cross-sectional view on the line A—B of Fig. 1;

Fig. 3 is a top plan view of the machine,
Fig. 4 is a front elevation thereof,
Fig. 5 is a cross-sectional view on the line C—D of Fig. 1.

Fig. 6 is an enlarged fragmentary sectional view taken on line 6—6 of Fig. 1, 60 showing the lead screw and cooperating plate for effecting the axial feeding of the tools, and

Fig. 7 is an enlarged fragmentary sectional view showing the cam-controlled clutch lever latch mechanism.

Referring to the several figures in detail, 70 wherein like numerals of reference indicate corresponding parts of the different figures shown, the structure comprises a die-head 1, having cross-wise guideways, within which is mounted to move, tool-carrying toolholder 27 with a straight circular threading tool 28, toolholder 29 with a taper, circular threading tool 30, toolholder 31 with a taper circular threading tool 32 and toolholder 33 with a circular cutting off tool.

On said die-head 1 is rotatably mounted 80 a cylindrical tubular body 2, having mounted on the same a spur gear 3 and having further a number of adjustable set-screws 35 for the later described action on the threading tools, and having further a number of set-screws 36 for the later described action in the cutting off tools.

A circular body 4 having a spur gear, 85 is fastened on said die-head 1 and is provided with a slot 26 for a purpose to be later set forth.

With said spur gear 3 on tubular body 2 is connected an idler gear 5, having clutch teeth 5^a, and also said spur gear on the circular body 4 is connected with an idler gear 6, having clutch teeth 6^a. Said idler gears 5 and 6 are rotatably mounted on a stud 7 which is fastened on headstock 22 of the machine. On said stud 7 is fastened a stop collar 8 with a stop shoulder 8^a. A catch 9 slidably mounted on a clutch lever 10 100 presses against said collar 8 and holds the said clutch lever 10 with the gear 5 fast in working position. A shaft 11 mounted rigidly with said clutch lever 10, is also connected with a handlever 12 on which a spring 13 is connected, said spring 13 at its other end is fastened to a stud 14, which is fastened on said headstock 22. A double pin 16 is slidably mounted in said tubular body 2, with its one end against said catch 110

- 9, while its other end is guidingly pressed against a number of cams, 1^a on said die-head 1.
- 5 A circular disc 15 with a number of cam notches is fastened in said tubular body 2, said cam notches acting on pin 25 in a manner to be more fully set forth later. An inner spindle 17 rigidly connected with said die-head 1, is provided with a collar 18 and carries a spring 19, which presses with one end against the collar 18, while its other end presses against a collar 21, which is fastened inside of a spindle 20, which carries in its cylindrical bore the axially slideable 10 inner spindle 17 by means of a key and keyway. Said headstock spindle 20 is rotatably mounted in headstock 22 of the machine and receives its rotary working motion by any suitable power drive attachment.
- 15 20 A lead screw 23, with a threaded part and of the same pitch as the pipe thread, to be cut is rigidly mounted on the headstock 22 of the machine. A plate 24 having a female thread is pressed in the threaded part of said lead screw 23, and is slideably mounted and held in guideways of said cylindrical body 4. A pin 25 fastened on said plate 24, is inserted in said slot opening 26, and is pressed against the cam notches of said disc 15.
- 25 30 A number of springs 37 located in openings on the die-head 1 bear with their one end against the bottom face of said openings and with their other end against shoulders of said toolholders 27, 29, 31 and 33.
- 35 A cover plate 38 fastened on said die-head 1 covers the front faces of said toolholders 27, 29, 31 and 33, thus holding them in the guideways of die-head 1, at the same time allowing the toolholders 27, 29, 31 and 33 an easy moving action. A clamping device 39 of the machine holds the piece 40, to be worked, in the desired position.
- 40 45 Assuming now that a pipe 40 has been clamped in position for working, and the headstock spindle 20 with the attached apparatus is running idle with the tools removed outside from the pipestock, then by operating the handlever 12, the clutch lever 10 will push the gear 5 towards the gear 6 and the clutch teeth 5^a will engage the clutch teeth 6^a. Thereby the idler gear 6 driven by the spurgear 4 will transmit its rotating motion upon the idler gear 5 and will transmit further the rotatable movement to the spurgear 3 in a ratio according to the difference of the gears, but in the same driving direction as the gear 4 on die-head 1. When operating the hand lever 12, the catch 9 and lever 10 with its stop shoulder will rest against the stop shoulder of stop collar 8 and 5 and 6 in operative position to each other and thereby give the tubular body 2 a greater 60 65 advance rotatable movement upon the die-
- head 1. Thus the cam notch of disc 15 moves away from under the pin 25 and the female thread plate 24 will by means of springs 24^a be pressed in the threaded part of the lead screw 23, which is in a fixed position on the head stock 22, and will thereby move sidewise relative to the die-head 1 in accordance to the thread pitch and in uniform to the pitch to be worked on the pipestock 40. This also causes an axially 70 75 sliding movement of the inner spindle 17, inside the rotating headstock spindle 20.
- This greater advance movement of tubular body 2 revolving on the now slower rotating die-head 1 brings first the short set screws 35 against the toolholders, and presses the same centerwards down against the pipestock 40. Toolholder 27, with its straight cylindrical threading tool 28 having a number of teeth with the profile of a 80 85 thread of desired pitch and also the toolholder 29 and 31, with their cylindrical tapering threading tools 30 and 32 are now guided against the pipestock 40 and cut a thread on the latter to a fraction of the 90 95 thread depth. Then acts the straight thread cutter 28 as a roughing tool, and the taper thread cutters 30 and 32 as finish or smoothing tools and taper the thread cut surface line according to the taper of tools 95 100 105 110 115 120 125 130 135 140 145 150 155 160 165 170 175 180 185 190 195 198 200 205 210 215 220 225 230 235 240 245 250 255 260 265 270 275 280 285 290 295 298 300 305 310 315 320 325 330 335 340 345 350 355 360 365 370 375 380 385 390 395 398 400 405 410 415 420 425 430 435 440 445 450 455 460 465 470 475 480 485 490 495 498 500 505 510 515 520 525 530 535 540 545 550 555 560 565 570 575 580 585 590 595 598 600 605 610 615 620 625 630 635 640 645 650 655 660 665 670 675 680 685 690 695 698 700 705 710 715 720 725 730 735 740 745 750 755 760 765 770 775 780 785 790 795 798 800 805 810 815 820 825 830 835 840 845 850 855 860 865 870 875 880 885 890 895 898 900 905 910 915 920 925 930 935 940 945 950 955 960 965 970 975 980 985 990 995 998 1000
- After the die-head 1 with the threading tools 28, 30, 32 has made a number of revolutions around the pipestock 40 the first set-screw 35 runs off from the end face of the toolholders 27, 29, and 31, and the springs 37, press the tools off from the pipestock 40. At the same time a cam notch of cylindrical disc 15 moves under the pin 25 and lifts the same with the plate 24 outwards 105 and releases the same from the engagement with the leadscrew 23, thereby bringing the spring 19 and inner spindle 17 in action, whereby the latter with the attached apparatus receives a backward movement in 110 axial direction inside the headstock spindle 20 thus moving the inner spindle 17 of the apparatus in a backward direction which is limited by the collar 21 inside of headstock spindle 20. The continued rotation of tubular body 2 and die-head 1 again moves the cam notch of disc 15 away from under the pin 25, and thus allows the plate 24 to slide back with its female threaded part in engagement with the threaded part of said lead screw 23 and again performs the thread leading movement of the apparatus. The threading tools in toolholders 27, 29 and 31, by means of the longer setscrew 35, are again guided against the pipestock 40 and perform now a second and deeper cut of thread.
- The aforesaid operations of the leadscrew parts are caused by the cam notches of disc 15, and of the toolholders 27, 29, and 31 with 130

the threading tools. By means of the successively longer setscrews 35 in body 2, and the repeated deeper cuts of thread, finally brings the thread on to work piece 40 to the desired finish. After this, the continued rotary movement of tubular body 2 and diehead 1 brings a sufficient release of the lead-screw parts thus keeping the inner spindle 17 with the apparatus in the rear position for a length of time, sufficient for the necessary operation of cutting the piece 40 in the desired length.

This will be accomplished by still continuing rotation of tubular body 2 and die-head 1, whereby set-screw 36 bearing against the outer end face of toolholder 33, which toolholder with its cutting off tool 34 is guided against the piece 40 to be worked. Thus the cutting off tool 34 severs the finished piece 40 from the pipestock, after which the double pin 16, by means of cam 1^a on die-head 1 is pressed against the catch 9 and moves the same downwards, thereby releasing the same from the stop-shoulder 8^a of stop collar 8. This movement allows the heretofore compressed spring 13 to become effective moving the handlever 12, whereby the clutch lever 10 disengages the gears 5 and 6, by removing the clutch teeth 5^a out of clutch teeth 6^a. Continued rotation of tubular body 2 on die-head 1 is now stopped until handlever 12 is again actuated to start the operation of the apparatus for working on the next work piece 40.

For the purpose of guiding the threading tools in continued outward or inward movements according to tapered thread, the toolholders 29 and 31 are each provided with a tapered outside face, on which the set screws 35 are guided thus reducing or enlarging the distance of the threading tools 30 and 32 from the surface of the piece 40, and accomplishing thereby a perfect and smooth tapering thread.

Having thus described my invention, what I claim as new therein and desire to secure by Letters Patent is:

1. In a threading and shearing device, a revoluble axially movable die-head, in combination with a set of threading tools, said threading tools having teeth for cutting a number of threads at once, and a shearing tool, said shearing tool having a tooth for cutting off the threaded piece to be worked, all of said threading and shearing tools being fastened in toolholders, secured to said die-head and simultaneously partaking of the several movements of said die-head and

means successively engaging said tool holders for radially actuating the same.

2. In a threading and shearing device, a revoluble axially movable die-head in combination with a set of threading tools and a shearing tool, said threading tools having teeth for cutting a number of threads at once, said shearing tool having a tooth for cutting off the threaded piece to be worked, toolholders for said threading and shearing tools, said toolholders being secured to said die-head and simultaneously partaking of the several movements of said die-head, said toolholders being radially displaceable by springs and set screws of different lengths for the threading tools, said threading tools having tapered end faces for making a conical thread, said toolholders being radially displaceable by springs and a set screw for the shearing tool, said shearing tool having a tapered end face for the inward movement thereof.

3. In a threading and shearing device a revoluble axially movable die-head in combination with a set of threading tools and a shearing tool, said threading tools having teeth for cutting a number of threads at once, said shearing tool having a tooth for cutting off the threaded piece to be worked, all said threading and shearing tools being secured to said die-head and simultaneously partaking of the several movements of said die-head, a tubular body having a plurality of set screws, for radially displacing said threading and shearing tools, said tubular body being revoluble on said die-head and adapted to receive an advancing movement by means of gears of different ratio.

4. In a threading and shearing device a revoluble axially movable die-head in combination with a lead screw device, fastened on a headstock of said device, a female screw plate engaging said lead screw, said engagement being timed and actuated by means of a set of cam notches, and a spring and stop collar for regulating the back slide motion of said die-head.

5. In a threading and shearing device a revoluble axially movable die-head in combination with a tubular body and lead screw device for actuating threading and shearing tools carried by said die head, a double pin, cams, a catch, a stop-collar formed with a stop shoulder, and a clutch lever and a hand lever therefor provided with a spring for automatically stopping the die-head operation.

VICTOR MÜLLER.
